UNITED STATES PATENT OFFICE.

SAMUEL D. BATES, OF LEWISBURG, PENNSYLVANIA.

HARVESTER.

SPECIFICATION forming part of Letters Patent No. 231,526, dated August 24, 1880.

Application filed December 8, 1879.

To all whom it may concern:

Be it known that I, SAMUEL D. BATES, of Lewisburg, in the county of Union and State of Pennsylvania, have invented certain new and useful Improvements in Harvesters; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to an improved material for the grain-platforms of harvesters and an improvement in the construction of the same.

It has been long known that it was a matter of great importance that the grain-platforms of harvesters should be so constructed that their upper surfaces should be as nearly perfectly smooth as possible, in order that the teeth of the rakes, as they move over the platform, should not in their movements be caught or interfered with by any irregularities of surface. When the platforms have been constructed of wood the boards which are employed have been joined together by some one or another of the various species of joints. From the action of heat and moisture upon such platforms great irregularities of surface are produced at the parts where the pieces of which the platform is composed are joined, the boards tending to warp and bend on the lines of their joints.

It has been attempted to construct from sheet metal harvester-platforms that should overcome these obstacles—that is to say, platforms which should have smooth upper surfaces and be without joints in the path of the rakes; but these have been found impracticable and have been abandoned, for while the sheet metal overcomes the unevenness of the platform of the harvester it at the same time so greatly increases the weight that it is practically worthless for this purpose.

I have succeeded in preserving the necessary lightness, durability, and strength of the platform, and in constructing it so that it shall have no joints or irregularities of surface in

the path of the rakes, by making it of paper 50 properly prepared to resist the action of the elements.

This invention also pertains to an improved combination and location of gearing devices for transmitting rotary motion from the main carrying and driving wheel of a one-wheeled harvester to the raking apparatus. In this respect it consists in combining substantially the following elements—viz., a main frame, upon which the driving-gear is mounted; a 60 quadrant-plate arranged to vibrate about the axis of the carrying and driving wheel; a pinion or driving shaft which is mounted upon the main frame, and about whose axis the main frame is hinged to the quadrant-plate; 65 a tubular standard which supports the raking apparatus; a vertical shaft mounted in said tubular standard to operate the rakes; a bevel-spur-wheel at the lower end of said shaft; a horizontal shaft mounted in the rake-standard 70 on a line parallel with the pinion or driving shaft; a bevel-pinion upon said horizontal shaft meshing with the bevel-wheel on the vertical shaft; a spur-gear wheel upon the horizontal shaft in the raking-standard; a spur-gear pinion on the platform end of the pinion or driving shaft; a spur-gear wheel which is mounted between the spur-pinion on the pinion or driving shaft and the spur-wheel on the horizontal shaft in the rake-standard, and 75 which converts the motion of the pinion on the driving-shaft into an opposite motion of the spur-wheel mounted in the rake-standard, whereby the rakes are operated with a steady 80 and uniform motion.

Figure 1 is a perspective view of my improved harvester. Fig. 2 is a perspective view of the gearing and shaft for driving the rakes. Fig. 3 is a view of the gearing and the casing surrounding the same.

The machine, in the construction of the draft-frame, the main frame, the cutter-frame, the driver's seat, and the means for connecting the main frame and cutter-frame to the driving and carrying wheel, is substantially similar 95 to that shown and described in another division of this application for patent for harvesters for which a patent, No. 219,795, was granted

on the 23d of September, 1879. Therefore the said parts need not be here described in detail.

The main frame is composed of an outside bar near the driving-wheel, an inside bar, A, near the platform and cutting apparatus, a front bar, A', and a rear bar, A².

B represents the finger-beam of the cutting apparatus, attached at the outer end to the divider C, which parts may be of any desired construction.

D is the grain-platform, constructed in the form of a quadrant, and provided with the side D', projecting or turned vertically upward from the base or bottom part.

E represents one of the rake-heads attached to the arm E', pivoted to the rake-head E², which is attached to the upper end of a vertical shaft mounted in the tubular standard F.

The rakes are revolved about the vertical shaft in such manner that they traverse the quadrant-platform in the well-known manner.

e e represent teeth attached to the revolving rake-heads E, which traverse the upper surface of the platform when the rake is in operation.

If the platform D be so constructed that there shall be upon its upper surface any projections or irregularities, the teeth e will be caught thereby and seriously interfere with the proper operations of the rake; and it is necessary, in order that the platform should not interfere thus with the rake, to make it either of a material which shall require no joints in the path of the rake, or which (if the platform be made with joints) shall not be acted upon by heat, moisture, or other warping and bending agencies.

I have succeeded in overcoming the difficulties that have heretofore been met with in the manufacture of harvester-platforms in these respects by constructing them of paper so arranged that there shall be no joints in the path of the rake to interfere with its movements. The paper for this purpose is either formed from pulp of the proper thickness or from sheets secured together, and when properly shaped it is treated by any of the well-known methods of protecting paper and similar substances from the deteriorating effects of heat and moisture. The paper when thus prepared affords the strength necessary for a platform. The platform is very durable, much lighter than when made of the ordinary materials now used, and can be manufactured at much less cost. Moreover, the side or flange D' can be formed in one and the same piece with the base or bottom part, D.

I am aware that paper has been applied to many uses—such as the manufacture of boats, the sides and dash-boards of carriages, &c.—and therefore I do not wish to be understood to claim such application of paper as my invention; but I believe that I am the first to have succeeded in constructing a harvester

grain-platform in such manner that it should be lighter and cheaper than those constructed of wood, and as strong and durable, and at the same time having no joints or irregularities of surface to interfere with the teeth of the rake.

G represents the pinion or driving shaft mounted on the main frame on a line substantially at right angles to the plane of rotation of the carrying and driving wheel H, and the main frame is hinged to the quadrant I about the axis of this shaft G. The quadrant or supporting plate I is supported upon the axle of the drive-wheel, and is arranged to support the shaft G, as shown in Fig. 3, and as fully shown and described in detail in the other aforesaid division of this application, for which the said Letters Patent No. 217,495 were granted.

K is a horizontal shaft mounted in the rake-standard on a line substantially parallel to the pinion-shaft G.

F' is a bevel-wheel attached to the lower end of the shaft which rotates the rakes, and which is mounted in the tubular standard F. Wheel F' is rotated by a bevel-pinion mounted on the shaft K.

K' is a spur-gear wheel rigidly attached to the shaft K at its outer end.

G' is a spur-gear pinion rigidly attached to the shaft G at the end next to the platform.

L is a spur-gear wheel mounted in a bracket, l, attached to the main frame between the pinion G' and the spur-wheel K'.

The shaft G is rotated by a driving-gear wheel, h, attached to the carrying-wheel H and engaging with the pinion g. The shaft G is arranged to be driven by an outer gear, as shown, and thus is operated with the advantages that are known to be incident to an outer-gear driving-wheel in contradistinction to one whose driving-teeth project inwardly.

N is the casing around the gearing.

When the power is thus taken from an outer gear-wheel the pinion G' cannot be permitted to engage directly with the wheel K, inasmuch as there would result a rotation of the rakes in the direction opposite to that which they require. In order to obviate such objectionable movement, I mount the wheel L' upon the main frame between the driving-pinion G' and the spur-wheel K', and thus I have a spur-gear connection for transmitting the power from a carrying and driving wheel having outwardly-projecting teeth to the raking apparatus.

I am aware that chains and other flexible devices have been used in various ways for driving the rakes of harvesters; but it is well known that such flexible devices are constantly strained and lengthened as they wear, and that the movements of the parts which they drive are varied according to such strain and wear.

It is also known that the rake of a harvester should be driven with a movement as even and uniform as possible, and that when driven

by chains it has an unsteady motion which causes it to slack as it takes hold of a sheaf and to jump or jerk as it leaves the sheaf, owing to the tendency of the chain to strain or 5 to be varied in its movement on account of the slack with which it is always provided when placed around the wheels. My invention has been made with this construction for driving the rakes by chain and the many objections incident to such construction directly 10 in view; and I have entirely obviated them by applying power from the driving-wheel to the raking apparatus through the shaft G, by which the main frame is pivoted to the quadrant-plate, the spur-pinion G' on the platform 15 end of said shaft G, the shaft K mounted in the rake-standard on a line parallel to the shaft G, the spur-gear wheel K' on the platform end of said shaft K, and the spur-wheel L mounted in the bracket l on the main frame, 20 between the pinion G' and the spur-wheel K'.

What I claim is—

1. In a self-raking harvester, a grain-plat-

form constructed of paper without joints in the path of the rakes, as set forth. 25

2. In a harvester, the combination, substantially as set forth, of the following elements, whereby the raking mechanism is adjustably connected with the drive-wheel and is driven thereby with a steady and uniform motion, 30 viz: the single drive-wheel H, the main frame A A' A², the plate I, supported upon the axle of the drive-wheel, the main driving-shaft G, about which the main frame is hinged, the rake-driving shaft K, parallel to the main 35 shaft G, spur-pinion G' on the inner end of shaft G, spur-wheel K' on the inner end of the rake-driving shaft K, and the intermediate spur-wheel L.

In testimony that I claim the foregoing I 40 have hereunto set my hand this 5th day of November, 1879.

SAMUEL D. BATES.
